UNITED STATES PATENT OFFICE.

JOHN NEPOMUC MOERATH, OF KILBURN PARK ROAD, COUNTY OF MIDDLE-
SEX, ENGLAND.

FURNACE.

SPECIFICATION forming part of Letters Patent No. 353,230, dated November 23, 1886.

Application filed September 10, 1886. Serial No. 213,190. (No model.) Patented in England November 10, 1883, No. 5,320, and November 21, 1884, No. 15,356; in Germany January 26, 1884, No. 31,157; in France April 18, 1884, No. 161,596, and in Belgium April 18, 1884, No. 64,868.

To all whom it may concern:

Be it known that I, JOHN NEPOMUC MOERATH, a subject of the Emperor of Austria, residing at Kilburn Park Road, in the county of Middlesex, England, civil engineer, have invented certain new and useful Improvements in Apparatus or Appliances in Connection with Fire-Places, Stoves, and Furnaces, (for which patents have been granted me in the following 10 countries, viz: Great Britain, dated November 10, 1883, No. 5,320; Germany, dated January 26, 1884, No. 31,157; France, dated April 18, 1884, No. 161,596; Belgium, dated April 18, 1884, No. 64,868; Great Britain, dated November 21, 1884, No. 15,356,) of which the following 15 is a specification.

The object of my invention is to economize fuel by obtaining a more perfect combustion and consequent consumption of smoke, as well 20 as preventing the adhesion of "clinkers" to the fire-bars. For this purpose I employ a system comprising the automatic suction of air, combined with aqueous vapor from a cistern in the ash-pit, which together are mixed in proper 25 proportions with the developed carbonic-oxide gases. This enables me to obtain, as aforesaid, more perfect combustion of fuel and the smoke evolved therefrom and greater heat, while at the same time effecting an immense saving of 30 fuel. To this end I employ a water pan or cistern placed in the ash-pit under the fire-grate, the vapor from which, in combination with the atmospheric air, is driven through hollow fire-bars with great velocity by an injector-shaped 35 air-sucker placed below the fire-bars and above the water pan or cistern. The hollow fire-bars are fitted with fire-clay for the purpose of super-heating and creating a draft by drawing air and vapor from the water through the air-sucker, and by this construction of fire-bar the 40 adhesion of clinkers is prevented.

In the accompanying drawings I have illustrated a convenient way of carrying my invention into effect, Figure 1 being a section of a 45 furnace showing my improvements applied thereto. Fig. 2 is an enlarged cross-section of one of the hollow fire-bars, taken on line $x-y$ of Fig. 1. Fig. 3 is a partial elevation of one end of a fire-bar, and Fig. 4 a plan view of Fig. 3.

Referring to the drawings, A is one of the 50 fire-bars formed in two halves longitudinally, (see Fig. 2,) and held together by bolts or rivets. Fire-clay A' is forced while in a plastic state into the apertures and recesses provided in the central and lower portion of the fire-bar, 55 and retained therein by its being forced through and hardening in the apertures marked A', Fig. 1, and having dovetailed edges, as best seen in the section at Fig. 2. A space, A³, is also provided at the upper edge of the fire-bar 60 and of dovetail section, and is also filled in with fire-clay.

A⁴ is the hollow space passing throughout the length of the fire-bar, and having side openings, A^{4x}, on each side alternately. At one end, 65 as shown at Fig. 1, the aperture A⁴ has a downward curve, and comes opposite and communicates with conical-shaped apertures B', formed in a resting bar or bearer, B, there being one such conical aperture in the length of such 70 bearer B for each fire-bar resting thereon.

C' are the injector-shaped air-suckers or tuyeres through which the air travels, as indicated by the arrows in Fig. 1. These tuyeres C' are preferably arranged, as shown, within 75 one another, and are curved or bent in an upward direction. The upper end of the inner tuyere, C', is smaller than the outer one, causing an induced current of air by giving a greater velocity to and sucking up of the air through 80 the larger tuyere, C. This injector-like tuyere may extend the length of the bearer B, or there may be several for each furnace.

In the ash-pit, and passing below the fire-bars, I provide a cistern or tank for containing 85 water supplied from any convenient source, which cistern may or may not be made removable, as preferred.

When in action, the air mixing with the vapor from the water is drawn or sucked up by 90 the injector-like double tuyeres C'. The action of these tuyeres tends as the current of air passes upward to quicken same, on the well-known induced-current principle, and passing through the conical apertures B' in the bearer 95 B enters the aperture A⁴ in the length of the fire-bar. The air and vapor pass by the side apertures, A^{4x}, into the fire in a highly-super-

heated condition, and the hydrogen and oxygen composing the vapor are here separated, whereby I obtain more perfect combustion, greater heat, &c., while at the same time it is to be observed that no steam, water, or heat is withdrawn from the boiler, to the detraction of its effective results, and provided (and so long as) water is supplied to the water-cistern the entire apparatus is wholly automatic in its action.

I claim as my invention—

The combination, with hollow fire-bars

having apertures, of the hollow bearer B, with openings leading into the hollow fire-bars, and the air-suckers or tuyeres C C' below the hollow bearer, and acting to heat the air and vapor from a water-pan and pass the same into the fire, substantially as specified. 15

JOHN NEPOMUC MOERATH.
